PUMP

Edward C. Dudley, Burbank, Calif., assignor to Thompson Ramo Wooldridge Inc., Cleveland, Ohio, a corporation of Ohio

Application March 17, 1954, Serial No. 416,793

9 Claims. (Cl. 103—42)

This invention relates to a pump of the angular piston and cylinder type adapted to be driven throughout a very wide range of speeds and still deliver a substantially constant flow at a predetermined pressure. Specifically, this invention relates to an angular piston and cylinder block pump having a combined flow valve and orifice arrangement for controlling the positions of the cylinder blocks relative to their end plates to reduce pump noise and to join the inlet and outlet ports of the pump whereby the pump will quickly deliver a substantially constant flow of fluid throughout a wide range of operating speeds.

In my co-pending application, Serial No. 174,611, filed July 19, 1950, now Patent No. 2,779,296, there is disclosed and claimed a hydraulic pump or motor of the angular piston and cylinder type having the cylinder blocks thereof urged against ported end walls of the pump casing to seal the inlet and outlet ports from each other. Fluid under pressure developed by the pump leaks into the space between the cylinder blocks for acting on the inner faces of the blocks to urge the blocks against the end faces of the casing. Portions of the outer faces of the blocks are vented to the pump inlet to reduce the area subjected to pressure and thereby provide a larger effective area on the inner faces for developing load or pressure between the sealing faces of the blocks and the casing.

It has now been found that high speed operation of the pump disclosed in my aforesaid application may develop pressures between the cylinder blocks to such an extent as to urge the blocks too tightly against the end walls of the pump thereby creating excess wear and producing undesired noise. In installations where the pump must be subjected to wide variations in speed ranges such as for example, in automotive power steering installations where the pump is driven by the automobile engine, the speed ratio may vary throughout such a wide range so as to create unnecessary pump wear. In such installations, the power steering apparatus requires sufficient fluid flow at sufficient pressure even at idling engine speeds and does not require any more than this minimum flow even at the highest engine speeds. Bypassing of the excess pumped fluid is not a satisfactory solution because this creates excessive heat and consumes power which is not used.

The present invention now eliminates the heretofore wasted power and prevents excessive heat development by venting the space between the cylinder blocks to a flow control valve in the discharge line of the pump. This valve carries an orifice to create the desired pressure differential and whenever this differential exceeds the predetermined amount, the space between the cylinder blocks is automatically vented to the pump inlet thereby permitting the cylinder blocks to be lifted off of the end faces of the pump casing and directly connecting the inlet and outlet ports of the pump whereupon the pump will deliver only the rated flow. The invention also includes a check or topping valve which will

2

dump the fluid when excessive pressures are developed to protect the pump and other parts in the hydraulic system.

It is then an object of this invention to provide an automatic flow control valve for angular piston and cylinder block type pumps which will regulate the positions of the cylinder blocks relative to their inlet and outlet ports for maintaining a predetermined delivery rate even throughout wide variations in speed rates of the pump.

A further object of this invention is to provide a combined pressure differential creating and flow regulating valve for angular piston and cylinder type pumps.

A still further object of this invention is to provide a controlled vent for the space between the cylinder blocks of an angular piston type pump to control the positions of the cylinder blocks relative to the sealing end faces of the pump housing whereby the inlet and outlet ports of the pump will be communicated through passages of varying capacity for maintaining a constant flow rate for the pump.

A further object of the invention is to eliminate heretofore encountered noise in the operation of angular piston and cylinder block type of pumps.

A specific object of this invention is to provide an orificed thimble valve in the discharge line of an angular piston and cylinder block type pump for venting the space between the cylinder blocks to a lesser pressure whenever the pressure differential on opposite sides of the orifice exceeds a predetermined differential to thereby permit the cylinder blocks to ride off of the sealing end faces of the pump housing for connecting the inlet and outlet ports of the pump.

Other and further objects of this invention will be apparent to those skilled in the art from the following detailed description of the annexed sheets of drawings which, by way of preferred example only, illustrate one embodiment of the invention.

On the drawings:

Figure 1 is a longitudinal cross-sectional view, with parts in elevation, of the angular piston and rotary cylinder block pump of this invention showing the cylinder blocks in maximum pumping position.

Figure 2 is a view similar to Figure 1 but showing the cylinder blocks in positions for joining the inlet and outlet ports of the pump to decrease the noise of operation and the pumping capacity of the pump in accordance with this invention.

Figure 3 is a transverse cross-sectional view with parts in elevation, taken along the line III—III of Figure 1.

Figure 4 is a transverse cross-sectional view with parts in elevation, taken along the line IV—IV of Figure 1.

Figure 5 is a perspective view of one of the cylinder blocks of the pump and illustrating several angular pistons in the block, the remaining pistons being removed.

Figure 6 is a transverse cross-sectional view taken along the line VI—VI of Figure 1.

Figure 7 is a longitudinal cross-sectional view of a modified pump arrangement according to this invention wherein the flow regulating valve is separate from the vent valve.

As shown on the drawings:

As shown in Figures 1 and 2, the pump 10 of this invention includes a housing 11 having cylindrical bores 12 and 13 extending inwardly from opposite ends thereof and disposed in angular relation to define an interior angle therebetween of more than 90° and less than 180°, preferably about 150°. The cylindrical bores 12 and 13 terminate respectively at shoulders 14 and 15 at their divergent ends and may or may not merge at their convergent ends. A space 16 is provided between the shoulders 14 and 15.

The bore 12 receives in rotatable relation thereon a cylindrical block 17 while the bore 13 receives a similar cylindrical block 18. These blocks are somewhat shorter than the bores and can move toward and away from the shoulders 14 and 15 respectively.

Each block 17 and 18 has a plurality of holes 19 extending axially through the block and disposed in a ring concentric to the axis of the block. These holes 19 receive the angled end legs of hollow angle type pistons 20. The knees of the pistons are disposed in the space 16 between the blocks and the legs of the pistons are of sufficient length so as to extend close to the outer end faces 21 and 22 respectively of the cylinder blocks 17 and 18 in the regions of the blocks where the inner faces 23 and 24 of the blocks are disposed substantially adjacent each other.

The ends of the housing 11 are closed by end plates or heads 25 and 26 respectively. Gaskets 27 are interposed between the end heads and the body to seal the interior of the body and bolts such as 28 secure the heads on the body.

As shown in Figure 3, the head 25 has an end face 29 confronting the end face 21 of the cylindrical blocks 17. This end face 29 has an arcuate inlet port 30 adapted to register with the holes 19 along those regions of the blocks where their faces 23 and 24 are spaced apart and where the ends of the pistons 20 are displaced inwardly from the outer end faces of the blocks. This arcuate port 30 is connected through a passage 31 in the end head 25 with the inlet boss 32 of the pump.

The end face 29 of the head 25 also has an arcuate port 33 communicating with the holes 19 of the cylinder blocks in the regions where the blocks are closest to each other and the pistons are closely adjacent the end face 21 of the block 17. This port 33 is connected through a passage 34 in the end head 25 with the outlet boss 35 of the head.

The central portion of the outer end face 21 of the cylinder block 17 is recessed at 36 and this recess communicates with the inlet port through a groove 30a in the end face 29 of the head 25. The diameter of the recess 36 is proportioned relative to the diameter of the end face 23 of the cylinder block 17 to create a differential pressure area to be acted upon by pressure existing in the space 16 for a purpose to be more fully herein-after described.

As shown in Figure 4, the end head 26 of the pump has an end face 37 confronting the end face 22 of the cylinder block 18 and equipped with an inlet port 38 opposing the port 30 and an outlet port 39 opposing the port 33. Thus, the opposite ends of the holes 19 simultaneously register with the ports 30 and 38 in the retracted positions of the pistons 20 while the opposite ends of the holes 19 simultaneously register with the outlet ports 33 and 39 in the extended positions of the pistons.

The cylinder block 18 has a splined blind recess 40 extending inwardly from the end wall 22 thereof and receiving a splined drive shaft 41. A counterbore 42 preferably surrounds the recess 40 in the end face 22 of the block 18 to size the effective area of the recess. The counterbore 42 is vented to the inlet port 38 through a groove 43 in the end face 37. The engaged spline teeth of the drive shaft 41 and the recess 40 provide passages joining the counterbore 42 with the bottom of the recess so that the effective area of the end face 22 of the cylinder block is proportioned relative to the effective area of the inner end face 24 of this block for a purpose to be hereinafter more fully described.

The drive shaft 41 is carried in bearings 45 seated in a bore 46 of the end head 26. A collar 48 on the shaft is disposed between the bearings 45 so that the bearings will also carry thrust loads.

An end plate 49 is bolted to the head 26 by means of cap screws 50 and carries a shaft seal 51.

While the shaft 41 is held against substantial axial movement relative to the head 26 by the bearings 45, the cylinder block 18 can shift toward and away from the shoulder 15 without interference from the shaft because the recess 40 extends beyond the end of the shaft. The space 16 between the cylinder blocks 17 and 18 receives fluid under pressure from the discharge ports 33 and 39 of the pump through leakage paths afforded between the holes 19 and the pistons 20 and between the bores 12 and 13 and the cylinder blocks 17 and 18. These leakage paths, of course, are also open to the inlet ports 30 and 38 so that the space 16 is normally maintained at a pressure equal to about one-half of the discharge pressure of the pump. This pressure acts on the inner end faces 23 and 24 of the cylinder blocks 17 and 18 to urge the blocks against the end heads 25 and 26. However, the recesses 36 and 42 in the outer end faces of the blocks are vented to pump inlet pressure and the areas of the end faces 21 and 22 which are not exposed to inlet pressure, and, therefore, less than the areas of the inner faces 23 and 24. The differential area thereby produced, controls the loading of the cylinders against their sealing end faces 29 and 37 of the end heads. As the pump discharge pressure increases, the sealing loads will also increase and while the areas are so designed as to maintain a film of fluid between the contacting end faces it has been found that this film may be squeezed to such an extent that excessive friction develops resulting in excessive wear and noise.

To avoid these wear and noise conditions and to insure delivery of constant hydraulic flow throughout a wide range of speeds, the pump casing 11 of this invention is provided with a depending boss portion 11a having a passage 52 communicating with the space 16 and intersected by a bore 53 in which is slidably mounted a thimble-type valve 54. The discharge port 35 of the head 25 is connected through a tube 55 with one end of the bore 53 while the other end of the bore receives a tube 56 for delivering the fluid from the pump. A shoulder 53a is provided in the bore 53 to act as a stop for the valve 54. A spring 57 which can be conveniently bottomed on the end of the tube 56, extends into the thimble valve 54 to be bottomed on the end wall 54a thereof for urging the valve away from the shoulder 53a. A groove 58 is provided around the cylindrical side wall 54b of the valve 54 and is adapted to register with the passageway 52 to accommodate flow through the passageway for discharge out of the open end of the passageway 52a.

An orifice 59 is provided in the end wall 54a of the valve and is sized for maintaining a predetermined pressure differential between the tubes 55 and 56.

The boss 11a of the casing 11 also has a recess 60 therein provided with a ball seat 61 and a passage 62 communicating with the bore 53 downstream from the valve 54. A passage 63 vents the recess. A plug 64 is threaded into the recess to bottom a spring 65 acting on a ball member 66 for urging the ball member 66 against the seat 61. This arrangement provides a ball relief or topping valve for venting the bore 53 downstream from the valve 54 whenever pressures exceed a predetermined amount. Thus, in such event, the ball check valve 66 will be unseated and the passageways 62 and 63 will be placed in communication thereby relieving excess pressures from the tube 56.

In the event that the pressure differential across the orifice 59 exceeds the predetermined maximum, the valve 54 will be moved under the influence of pressure acting on the end wall 54a thereof against the spring load 57 to be bottomed against the shoulder 53a whereupon the groove 58 will open the passage 52 to vent the space 16 to a lower pressure such as atmospheric pressure or pump inlet pressure. This venting of the space 16 will

reduce the pressure in the space and will permit the cylinder blocks 17 and 18 to move inwardly toward their shoulders 14 and 15. Such inward movement of the blocks will, of course, be under the influence of the discharge pressure acting on the outer faces 21 and 22 of the blocks and will space these outer faces from their coacting sealing faces 29 and 37. The inlet and outlet ports 30 and 33, 38 and 39 of the pump will thereby be placed in communication and fluid will be metered therebetween. In this manner, the pump is automatically regulated to deliver only a predetermined flow rate since excess delivery will result in the shifting of the valve 54 and the lessening of the flow through the tube 55 even when the pump speeds would ordinarily call for a higher flow rate. The ball check valve 66 serves as a topping valve or safety valve in the event that the metering valve 54 does not sufficiently cut down the pump pressure by effecting the unseating of the cylinders blocks 17 and 18.

In the modified pump 70 of Figure 7, parts identical with parts of the pump 10 have been marked with the same reference numerals. As therein shown, the depending boss 11a of the casing 11 has a second bore 71 therethrough above the bore 53 and the tube 55 has a branch 72 connected to one end of this bore 71 while the other end is closed by a vented plug 73. A solid cylindrical valve 74 is slidable in the bore 71 and has a groove 75 therearound for registering with the passage 52. This passage 52 instead of continuing to the bore 53 as in the pump 10, extends to a passage 76 opening to the atmosphere or pump inlet. A spring 77 urges the valve 74 to move the groove 75 thereof out of registration with the passage 52 until pump pressure in the tube 72 is high enough to act on the solid end face of the valve 74 for shifting the valve against the spring bias whereupon the space 16 will be vented to the passage 76.

The valve 54 in the bore 53 when shifted by an increased pressure drop across its orifice 59 due to increased flow will uncover a vent passage 78 to relieve excess flow as desired.

The relief valve 66 operates in the same manner as in the pump 10 to protect against excessive pressures in the tube 56.

The pump 70 thus has a separate valve 74 controlled by pump pressure upstream from the flow valve 54 and the flow valve dumps the excess fluid whenever the flow rate increases beyond the amount desired. This arrangement responds quickly to correct excess flow conditions but the excess fluid is pumped before being released in the event the valve 74 is not first shifted to cause venting of the space 16 and axial shifting of the cylinder blocks 17 and 18 to decrease the pump output.

It will be understood that variations and modifications may be effected without departing from the scope of the novel concepts of this invention.

I claim as my invention:

1. In a hydraulic machine having a casing with communicating angularly disposed cylindrical bores, cylinders rotatable and axially shiftable in said bores, said cylinders having axially extending holes therethrough, angular pistons slidably mounted in said holes, means providing a space in said casing receiving said pistons therethrough and disposed between said cylinders, end walls in said casing receiving the outer ends of the cylinders thereagainst, said casing having an inlet and an outlet port communicating through an end wall with the holes in the cylinders respectively along areas where the pistons are retracted from the outer ends of the cylinders and along areas where the pistons are adjacent the outer ends of the cylinders, a flow metering valve in fluid communication with said outlet port and having a fixed orifice subjected to the discharge pressure of the pump and a relief passageway in communication with the space between the cylinders in the pump casing, and means

biasing the metering valve to close said relief passageway, said metering valve being shiftable whenever the pressure differential across the fixed orifice thereof exceeds a predetermined amount to selectively open the relief passageway whereupon the cylinder blocks will ride off of the end faces in the pump to meter flow between the inlet and outlet ports.

2. A hydraulic machine comprising a casing having communicating bores in angular relation, cylinder blocks rotatable and slidable in said bores, end walls on said casing adapted to receive the outer end faces of the cylinder blocks in sealing relation, said casing having a space between said cylinder blocks, said cylinder blocks having a plurality of axial holes therethrough, angled pistons having the angled legs thereof respectively slidably mounted in said holes, means for rotating said cylinder blocks to shift the positions of the ends of the pistons relative to the outer end faces of the blocks for effecting a pumping through said holes, said space between the cylinder blocks communicating through leakage paths with the fluid discharged from the pump, said pump having an inlet and an outlet respectively communicating with the outer end faces of the cylinder blocks along separated areas thereof where the pistons are retracted inwardly from the end faces and where the pistons are adjacent the end faces, a flow metering valve having a fixed orifice in the pump outlet adapted to maintain a predetermined pressure differential on opposite sides thereof, said flow metering valve having a passage selectively registering with a relief passage connected to the space between the cylinder blocks whenever the pressure differential across said orifice exceeds a predetermined amount, thereby to relieve the pressure in said space between the cylinder blocks and permit the discharge pressure to move the blocks toward each other and meter flow between the outlet and inlet of the pump.

3. A pump having a casing with interconnected bores at an angle of more than 90° and less than 180°, cylinder blocks rotatable and shiftable in said bores, stops limiting the inward shifting of the cylinder blocks in said bores to provide a space between the blocks, end heads on said pump adapted to receive the outer faces of the cylinder blocks thereagainst, said cylinder blocks having a plurality of axially extending holes therethrough, hollow angled pistons having the angled legs thereof slidably mounted in said holes and interconnecting said blocks, a drive shaft rotatably carried by one of said ends, said outer faces of the cylinder blocks being recessed inwardly from said holes, said shaft projecting into one of said recesses and being coupled with the cylinder block to drive the block while accommodating axial shifting of the block thereon, said end heads having arcuate inlet and outlet ports respectively registering with the holes in the cylinder blocks at areas where the pistons are retracted from the end faces and at areas where the pistons are adjacent the end faces, passages in said end heads connecting the recesses in the cylinder blocks with the inlet ports thereof, one of said inlets having an inlet boss and an outlet boss respectively communicating with the inlet and outlet ports, means defining a passage in said casing connecting the space between the cylinder blocks to a lower pressure, a valve in said passage, means biasing said valve to closed position, said valve being exposed to a pump discharge pressure and being shiftable under the influence of such pressure against said biasing means to open the passage and communicate the space to lower pressure whenever the pump discharge pressure exceeds a predetermined maximum whereby pressure against the outer end faces of the cylinder blocks will cause the blocks to ride off of the end heads and meter flow between the inlet and outlet ports to reduce the pumping capacity of the pump.

4. In combination, an angular piston and rotary cylinder block type pump including a housing having end walls with sealing faces, an inlet, an outlet and a relief

passage, a pair of spaced axially bored cylinder blocks rotatably journaled in said housing and defining a space therebetween in the housing, a plurality of angular pistons slidably mounted in said bores to provide suction at said inlet and pressure at said outlet, said space being subjected to outlet pump pressure for urging said cylinder blocks against said sealing faces, a pressure responsive flow controlling valve positioned between said housing space and said relief passage and exposed to said outlet to selectively connect the space in the housing between the cylinder blocks with said relief passage whenever the flow delivery of the pump exceeds a predetermined maximum to permit the cylinder blocks to ride off of the sealing faces.

5. In combination, an angular piston and rotary cylinder block type pump including a pump housing having a pair of communicating angularly disposed bores, an outlet flow passage and a relief passage registering with said bores, a pair of cylinder blocks having axial bores, said blocks being rotatably mounted and axially shiftable in said pump housing bores and defining a space therebetween subjected to pump discharge pressure, a plurality of angled pistons slidably mounted in the bores in said cylinder blocks, end plates closing the open ends of said angularly disposed bores in said pump housing to form pumping chambers for said pump, a shiftable, orificed, flow metering valve member movably positioned in said outlet flow passage and subjected to pump discharge pressure and also interposed in said relief passage to close said relief passage in an upstream position and open said relief passage in a downstream position, means biasing said valve upstream in said flow passage, said valve adapted to move to downstream position whenever the delivery rate of said pump exceeds a predetermined amount.

6. In combination, an angular piston and rotary cylinder block type pump including a pump housing having a pair of communicating angularly disposed bores, an outlet flow passage and a relief passage registering with said bores, a pair of cylinder blocks having bores therethrough, said blocks being rotatably mounted and axially shiftable in said pump housing bores and defining a space therebetween subjected to pump discharge pressure, a plurality of angled pistons slidably mounted in the bores in said cylinder blocks, end plates having inlet and outlet ports subjected to pump pressure closing the open ends of said angularly disposed bores in said pump housing, a flow regulating valve interposed in said relief passage to control flow through said relief passage and having a valve control body movably located in said outlet flow passage and adapted to move in said outlet flow passage to open said valve in response to a predetermined maximum pump discharge flow rate and to connect said space with said relief passage whenever the flow rate of the pump reaches a predetermined maximum, thereby reducing the pressure in said space to permit the cylinder blocks to move toward each other and decrease the pumping capacity of the pump.

7. In combination, an angular piston and rotary cylinder block type pump including a pump housing having a discharge passage and a relief passage, a pair of rotatable, axially shiftable, relatively inclined cylinder blocks in said housing defining a space therebetween, a plurality of angular pistons slidably mounted in said cylinder blocks, a valve having a shiftable control body in said discharge passage exposed to discharge flow, said valve interposed in said relief passage to selectively connect the space between said cylinder blocks with said relief passage to a lower pressure whenever the flow rate of the pump reaches a predetermined maximum to move said valve control body to thereby maintain a predetermined pump flow rate, and a relief valve downstream of said

flow metering valve to prevent the discharge pressure of said pump from reaching a predetermined maximum.

8. In combination, a pump of the angular piston and rotary cylinder block type including a pump housing 5 having a pair of intercommunicating angularly disposed bores, a pump discharge passage, a pump relief passage intersecting said discharge passage, a pair of rotatable axially shiftable cylinder blocks having a plurality of axial bores therethrough, said cylinder blocks defining a space therebetween subject to pump discharge pressure and connecting to said relief passage, a plurality of angular pistons in said bores, end plates having inlet and outlet ports formed therein connected to the discharge passage and closing the ends of the bores in said pump housing and receiving said cylinder blocks in rotative sealing engagement thereagainst, a flow regulating valve body slidably mounted in said pump discharge passage and having a discharge flow passage therethrough to pass discharge fluid through said pump discharge passage and 10 having a lateral relief passage to permit flow through said pump relief passage when aligned therewith for relieving pressure in said space, and a spring urging said valve body upstream in said pump discharge passage and said valve relief passage out of alignment with said pump relief passage whereby a predetermined flow through said valve flow passage would cause alignment to relieve said space and to prevent the discharge of said pump from reaching a predetermined maximum.
9. In an angular piston and rotary cylinder block type 15 pump including a pump housing having a pair of intercommunicating angularly disposed bores, end plates closing the bores, one of said plates having an inlet and an outlet, a discharge conduit connected to said outlet, a pair of rotatably mounted axially shiftable cylinder blocks 20 having a plurality of axial bores therethrough riding on the end faces of said end plates and defining a space therebetween subjected to pump discharge pressure from leakage paths between said cylinder blocks and pump housing, a plurality of angled pistons in said cylinder block bores, a passage leading from said space, a pressure responsive valve in said passage and exposed to pump discharge pressure in said discharge conduit for selectively opening the passage and reducing the pressure in said space between said cylinder blocks to permit said cylinder blocks to ride off the end faces of said end plates 25 to reduce the noise of said pump and limit the maximum output of said pump when the pump discharge pressure reaches a predetermined maximum pressure, and pressure relief means in said conduit operative to directly relieve pressure therefrom at a predetermined maximum pressure.
